US0D1083381S

(12) **United States Design Patent** (10) **Patent No.:** **US D1,083,381 S**
(45) **Date of Patent:** **** Jul. 15, 2025**

(54) **CONTAINER**

(71) Applicant: **YETI Coolers, LLC**, Austin, TX (US)

(72) Inventors: **Mark D. Miller**, San Marcos, TX (US);
Nicholas James Lombardi, Austin, TX (US); **Steven M. Scott**, Austin, TX (US); **Elizabeth Ruchte**, Austin, TX (US); **Andrew J. Winterhalter**, Austin, TX (US); **Liza Morris**, Austin, TX (US)

(73) Assignee: **YETI Coolers, LLC**, Austin, TX (US)

(**) Term: **15 Years**

(21) Appl. No.: **29/946,410**

(22) Filed: **Jun. 7, 2024**

Related U.S. Application Data

(63) Continuation of application No. 29/861,555, filed on Nov. 30, 2022, now Pat. No. Des. 1,036,119.

(51) **LOC (15) Cl.** **03-01**

(52) **U.S. Cl.**

USPC **D3/294**; D3/276; D3/905

CLAIM

The ornamental design for a container as shown and described.

DESCRIPTION

FIG. 1 is a top, front, right perspective view of a container showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines immediately adjacent to the shaded area define the bounds of the claimed design and form no part thereof. The broken lines depicting the remainder of the container form no part of the claimed design.

1 Claim, 7 Drawing Sheets
